CLAIM

The ornamental design for a chair, as shown and described.

DESCRIPTION

FIG. 1 is a perspective view of my ornamental design with broken lines showing environmental structure, which is shown for illustrative purposes only and form no part of the claimed design;

FIG. 2 is a front elevation view of the ornamental design of FIG. 1;

FIG. 3 is a rear elevation view of the ornamental design of FIG. 1;

FIG. 4 is a left elevation view of the ornamental design of FIG. 1;

FIG. 5 is a right elevation view of the ornamental design of FIG. 1;

FIG. 6 is a top view of the ornamental design of FIG. 1; and,

FIG. 7 is a bottom view of the ornamental design of FIG. 1.
